UNITED STATES PATENT OFFICE

LEE ROY ROBERTS, OF LOS ANGELES, CALIFORNIA, ASSIGNOR OF TWENTY PER CENT TO CLARENCE B. ROBERTS, TWENTY PER CENT TO ANDREW B. WATSON, AND TWENTY PER CENT TO LOUIS M. HEUERTZ, ALL OF LOS ANGELES, CALIFORNIA

NECKTIE FASTENER

Application filed January 28, 1932. Serial No. 589,423.

My invention relates to a necktie fastener in which the fastener forms an ornamental holder for the necktie at the collar.

My fastener pertains to a type in which 5 the two ends of the necktie are inserted through a ring-like or tubular structure, the rings or the tubes being used to secure the necktie in position, and with these I provide devices which will secure the holder in 10 a snug position as regards the collar and the neckband of the collar.

In the above type of fastener an object and 15 feature of my invention is forming a fastener or holder of a tubular or ring-like type in which an ornamental panel may be made in the form of a cameo.

Another object and feature of my invention is the formation of supporting wings 20 which extend laterally from the device for binding a tie, these being adapted to fit against the neckband of a collar. In conjunction with these wings I provide a pair 25 of resilient pins which are adapted to engage the points of a down-turned collar. The wings and the pins hold the device in snug position on the collar.

Another detailed feature of my invention 30 is forming the tubular structure somewhat tapered to bind the necktie at a narrow portion of such tie. And a further feature comprises a binding or locking device having 35 a pivoted dog or pawl structure which may be manipulated by a finger-operated device to press into the necktie and thereby secure the tubular holder in position.

Another object and feature of my invention relates to a modification in which instead of a tubular holder for the tie, a series 40 of ring-like devices are formed of wire, there preferably being two more or less distinct rings at the top for the two parts of the tie passing around the neckband, and a single ring-like element at the bottom for the two ends of the tie. In order to make this 45 device ornamental I secure a panel to the front of the wire structure, which panel may be ornamental.

Another object and feature of my invention 50 is the construction of a fastener in which the tube is provided with a hinged gate at

the back, which gate when opened allows inserting of the two ends of the necktie, the gate when closed also operating as a clamp for the tie.

My invention is illustrated in connection 55 with the accompanying drawings, in which:

Fig. 1 is a front elevation of my device applied to a necktie and a collar;

Fig. 2 is a rear elevation of the device in 60 one form;

Fig. 3 is a vertical section on the line 3—3 of Fig. 1 in the direction of the arrows;

Fig. 4 is a front elevation taken in the direction of the arrow 4 of Fig. 5 of a modified construction, showing a wire support for 65 the ties;

Fig. 5 is a side elevation taken in the direction of the arrow 5 of Fig. 4;

Fig. 6 is a rear elevation taken in the direction of the arrow 6 of Fig. 5;

Fig. 7 is an elevation of a modification having a gate in the rear of the tube;

Fig. 8 is a rear elevation of the construction of Fig. 7;

Fig. 9 is a vertical section on the line 9—9 75 of Fig. 7 in the direction of the arrows;

Fig. 10 is a transverse section on the line 10—10 of Figs. 8 or 9;

Fig. 11 is a plan taken in the direction of the arrow 11 of Fig. 8, showing the gate 80 opened for inserting the ends of the tie.

Referring first to the construction of Figs. 1, 2, and 3, I employ a tapered tube 11 which is wider at the top portion 12 than at the bottom 13. This device is of a greater diameter on the measurement 14 than on the measurement 15 and thus forms a flat tube preferably of oval cross section. Extending upwardly from the tube at the front there are a pair of wings 16, these wings being joined in the center part 17 and having a concave upper edge 18. Secured to the center part of the wings there are a pair of pins 19, these having prong ends 20 with sharpened points 21, and each having a small coil spring 85 22. There are two pins connected at the center by a center wire 23, which wire is secured by soldering or the like as indicated at 24 to the center portion of the wings, the wire preferably having a kink 25.

A necktie latch or lock designated 26 employs a pivot 27 and has a dog or pawl 28 extending into the tube 11 from the back. A finger grip end 29 slightly bent as indicated at 30 for engagement by a finger or thumb nail is used to manipulate the dog or pawl. In the gripping relation the finger grip end fits snugly in an opening 31 in the back of the tube and may be readily tilted 10 outwardly to release a necktie. On the front of the tube there is an ornamental panel 32 which may be in the form of a cameo or any other desirable ornamental feature.

In the use of the device, as above mentioned, the necktie has two portions 33, 34, which encircle a neckband 35 of a collar 36. This collar is illustrated as having depending points 37. The necktie is not knotted but the two ends are drawn through the flattened 20 tube, the pawl preferably being turned to allow free passage of such ends. The ends are allowed to hang freely as indicated at 38.

The wings 16 are designed to fit snugly underneath the collar close to the neckband. 25 The points 21 of the pins are thrust in the under side of the downwardly projecting points 37 of the collar and thus hold the tube upwardly at the notched portion of the collar as illustrated in Fig. 1. When the device 30 is in place and the tie properly drawn through the tube the clamp 26 is operated to clamp the tube and thus hold the necktie fastener to the necktie. This also aids in retaining the device in a snug position in reference to 35 the collar.

In the construction illustrated in Figs. 4, 5, and 6, the device for holding the necktie is formed of bent wire and preferably has what may be designated as a pair of upper 40 loops 40 and what may be considered as a lower single loop 41. In making these loops a single wire is used, the ends being secured at 42. The wires are then bent to form wings 43, such wings having an upper wire 44 and 45 a lower wire 45 having a reverse bent connection 46. These wires may be considered as occupying a vertical plane. From the portions 45 there are two rearwardly bent portions 47 which are nearly horizontal or 50 at right angles to the plane made by the wires 44 and 45. Then there are laterally diverging sections 48, a return bend 49 toward the front, a front portion 50 of the loop, the wire from this front portion extending 55 vertically downwardly as indicated at 51, this being on the front portion of the device. At the bottom of the straight section 51 a loop 41 is formed by an outwardly extending portion of the wire 52, this having a reverse 60 bend 53 at the outer side and a return rear portion 54. There are then two upwardly bent parts 55 having a return bend 56 at the top.

This bent wire by itself when made of sufficiently stiff wire is quite rigid but in order

to further strengthen the device I attach a panel plate 57 on the front of the bent wire loops. This panel plate is soldered or welded to the upper central portion 42, 44, 45 of the wings. It is also welded to the front portion 70 of the loop 40 which comprises the wires 50, and it is also welded to the vertical wires 51 and to the front wires 52 of the loops 41. Pins designated generally at 58 have sharpened points 59 with a coiled spring 60. There 75 is a horizontal part 61 of these wires which is welded or soldered to the back of the ornamental panel or plate.

In the use of this device the two parts of the necktie which are drawn around the collar band are first passed each through one of the loops 40, which loops have the wires 47 at the center, the portions of the necktie are then drawn downwardly between the front wires 51 and the rear wires 55, the front 80 wires having also the panel secured thereto, and the loose and free ends are pulled downwardly through the bottom loop 41, this being formed by the wire portions 52, 53, and 54. The wings formed of bent wire fit underneath the collar adjacent the neckband. 90 The points of the pins are inserted on the underside of the points of the collar and thus the device is held in a snug position on the collar adjacent the neckband with the unknotted necktie extending through such device. The ornamental panel in the front hides and obscures all of the wires used to form the loops through which the necktie 95 is passed.

The upwardly extending parallel wires 55 which extend upwardly from the bottom loop 41 and which have a reverse bend at the top have a tension tending to bring the reverse bend into contact with the back of the necktie threaded through the upper pair and the single lower loop, which construction exerts a pressure on the necktie and functions somewhat as a latch or lock for the tie. The pressure may be relieved for threading the 110 tie by engaging these vertically extending wires adjacent their reverse bends and pulling them toward the rear when the necktie is being fitted through the loops.

In the construction of Figs. 7 through 11 115 I employ a tapered tube 70 which has a front section 71 and a back 72. This back has a hinged gate 73, there being small ears 74 on the back portion and on the gate through which pintles extend. The gate has a slightly outwardly bent edge 75 forming a finger grip for opening such gate. There is a transverse depression 76, having an internal hump, in the back of the gate in which fits the free end 77 of a leaf spring 78, the end 79 of such spring being fixed to the sides 80 of the tube.

This construction is provided also with an ornamental panel 81 in the front. The front of the tube has an upwardly extending 120

central extension 82 from which there are diverging wings 83. A pair of pins 84 have a common central section 85 welded or soldered as indicated at 86 to the center portion of the front of the tube. The pins are illustrated as having resilient coils 87 and sharpened points 88. In this construction the wings fit adjacent the neckband of a collar and the points of the pins engage the inside of the points of the collar, thus holding the device in position. With this arrangement the gate at the back may be readily opened, which allows inserting of the two ends of the necktie in the tube without threading the tie through the tube. This is, therefore, a simple way of securing the tie in place and avoids crushing the tie. The depression 76 which forms an internal hump engages and retains the tie in position, as illustrated in Figs. 9 and 10.

Various changes may be made in the details of construction without departing from the spirit or scope of the invention as defined by the appended claims.

I claim:

1. A necktie fastener having a ring structure, wings connected thereto at the upper end to extend partly around the neckband of a collar, a pair of resilient pins having sharpened points extending downwardly from the wings and on opposite sides of the ring, said pins being adapted to engage the underside of the points of a collar, said ring being adapted for threading the two ends of a necktie therethrough, means to press against the underside of the tie, and an ornamental panel secured on the front of the ring and covering a portion of the tie.

2. A necktie fastener having a tubular structure with a pair of laterally extending wings at the top, said wings being adapted to fit underneath a down-turned collar adjacent the neckband, the tube being adapted for threading two ends of a necktie therethrough, pins secured at the center portion of the wings, said pins having sharpened points to engage the depending points of the collar, and means to clamp the tie in said tubular structure.

3. A necktie fastener having a flattened tapered tube wider at the top than at the bottom, a pair of laterally extending wings connected to the upper part of the tube, said wings being adapted to engage underneath a collar adjacent the neckband, a pair of pins connected together and the connected portion being attached to the center portion of the wings, the pins having points to engage the depending points of the collar, the tube being adapted to accommodate the threaded ends of a necktie, a pivotally mounted clamp in the back of the tube having means to engage the tie and hold the tie in the tube.

4. A necktie fastener as claimed in claim 3, said clamp having a pawl adapted to extend

transversely partly across the tube to engage the tie, and having a finger-operated end fitting in a slot in the back of the tube.

5. A necktie fastener having a flat tapering tube wider at the top than the bottom, the front side of the tube being longer than the rear side and having a pair of laterally extending wings connected thereto, the wings being curved to conform to the neckband of a collar, a pair of pins having a connecting portion attached to the center part of the projecting portion of the tube, said pins being resilient and having sharpened points to engage on the under side of the points of the collar, the back of the tube having a slot, a locking device for the tie having a pivotally mounted pawl to extend transversely partly across the tube from the back and having a finger grip end to fit in said slot, with means for engaging same by a fingernail, the tube being adapted to receive the two ends of a necktie threaded therethrough, and the front of the tube having an ornamental panel.

6. A necktie fastener having a pair of rings in horizontal alignment formed of wire, the wire extending from the center portion of the rings and forming a pair of laterally extending wings, additional wires depending from the rings and forming substantially a lower ring, a panel secured to the upper and lower rings, the two upper rings being each adapted to receive one end of a necktie threaded therethrough, and the lower ring to receive the two ends of the necktie, the wings being adapted to fit adjacent the neckband of a collar.

7. A necktie fastener having a structure formed of wire with two parallel upper rings, the wire from the meeting edges of said rings being bent laterally with a reverse bend to form a pair of laterally extending wings, another pair of wires from the junction portion of the two upper rings extending downwardly and being bent to form substantially a lower ring with an upwardly projecting portion, a panel secured to the upper and lower rings and to the downwardly extending wires from the upper rings, the two upper rings being adapted each to receive the end of a necktie threaded therethrough, and the lower ring being adapted to receive both ends of the necktie, a pair of pins secured to the panel and having points to engage the points of a collar, said wings being adapted to fit adjacent the neckband of a collar.

8. A necktie fastener having a wire bent into a lower substantially horizontal loop with two wires extending upwardly at the back of the loop with a reverse bend and two wires extending upwardly in the front of the loop, a pair of rings formed by the two upwardly extending wires on the front, said rings being in substantially a horizontal plane, the adjacent wires of the loops at the center being bent laterally and returned with

a reverse bend to form a pair of wings, the ends of the wires being secured together at the center portion of the wings, a panel attached to the front wires and to the upper and 5 lower rings, a pair of pins attached to the panel, the points of the pins being adapted to engage the points of a collar, the upwardly extending wires at the back being under tension to engage a necktie threaded 10 through said rings.

9. A necktie fastener having a tubular structure tapered from one end toward the opposite end, said structure having an opening in the back with a gate pivoted to one 15 side of said opening to form a closure for said opening, means to hold the gate in its closed position, said opening and closing gate facilitating fitting the ends of a necktie through the tubular structure, wings connected to the upper portion of the tubular structure and adapted to fit adjacent the neckband of a collar, and pins secured to the tubular structure to engage the underside of the collar.

25. In testimony whereof I have signed my name to this specification.

LEE ROY ROBERTS.
